UNITED STATES PATENT OFFICE

148,703

DESIGN FOR A VEGETABLE CUTTER

Carl B. Ingram, El Monte, and Chester T. Ingram,
Los Angeles, Calif.

Application May 8, 1946, Serial No. 129,453

Term of patent 3½ years

(Cl. D89—1)

To all whom it may concern:

Be it known that we, Carl B. Ingram and Chester T. Ingram, both citizens of the United States of America, residing in the cities of El Monte and Los Angeles, respectively, in the county of Los Angeles, State of California, have invented a new, original, and ornamental Design for a Vegetable Cutter, of which the following is a specification, reference being had to the accompanying drawings, forming a part thereof.

We claim:

The ornamental design for a vegetable cutter, substantially as shown.

CARL B. INGRAM.
CHESTER T. INGRAM.
